GAME

Dennie Robert Baker, Richmond, Va.

Application May 19, 1936, Serial No. 81,106

4 Claims. (Cl. 273—45)

This invention relates to games and more particularly to games operated by plungers or the like.

One of the objects of this invention is the provision of a game similar to bowling.

Another object of this invention is the provision of a substantially miniature bowling game.

A still further object of this invention is the provision of a miniature bowling game constructed in a container, and provided with miniature balls that may be expelled from a plunger in the direction of pins, the latter being adapted to fall upon substantial contact with a ball, and mechanical means provided whereby the pins may be re-set to a normal position, and the balls so expelled returned to a container where they are held for play.

Other objects and features will more fully appear from the following description and accompanying drawings, in which:

Fig. 1 is a top plan view of the machine, showing alleys for balls;

Fig. 2 a side elevation, certain parts having been broken away;

Fig. 3 a top plan view along line 3—3 of Fig. 2; Fig. 4 an end view taken along line 4—4 of Fig. 1;

Fig. 5 a sectional view along line 5—5 of Fig. 4;

Fig. 6 a detailed view of the plunger construction taken along line 6—6 of Fig. 4; and Figs. 7 and 8 showing detailed views of the pin respectively urged upwardly and onto the seat.

Referring to the drawings, the device consists of a top 1, provided with sides 2, ends 3, and a bottom 4, all of which form a rectangular box or container that is supported by legs 5.

The top 1 is provided with a plurality of holes 6 through which project and operate, respectively, pins 7; more fully explained hereinafter.

An aperture 8 is located directly in front of the hole 6, the latter being at the apex of an imaginary triangle formed by said holes, and is adapted to receive a ball 9 (see Fig. 2) that has been ejected from a plunger 10 movable in a casing 11 that is superimposed upon the top of said device.

Referring to Fig. 2 a member 12 is pivotally connected to an axle 13 secured to said sides; said member being located directly below aperture 8 through which the ball 9 or other balls may pass. A tongue 14 on said member 12 extends downwardly therefrom and bears against a bar 15 connected in pivotal fashion to an axle 16 secured to one of the sides 2. The lower end of bar 15 is pivotally connected to one end of a rod 17 and

the other end is movable in a bearing 17'. The rod 17 has extending at right angles therefrom and respectively to the rear of the pins trippers 18. A spring 19 is secured to end 3 and one of the trippers 18; said spring (when no ball engages member 12) maintaining member 12 substantially parallel to said top.

In operative relation with, and below member 12, is a track 20, provided at one end with a flanged receptacle 21 for receiving the ball as it passes through aperture 8 to the member 12 from whence it passes to the track 20. Track 20 is pivoted to an axle 22 secured to sides 2. From one end of said track projects a support 23 to which is pivoted a hanger 24 connecting a base 25 to which is secured a plurality of stops 26 in spaced relation to each other, and adapted to support, at times, respectively, the pins 7; that project through the apertures 6 in top 1; said apertures being slightly larger than the pins.

The base 25 is provided with holes through which guides 27, secured to the bottom, pass so as to maintain the base parallel to the bottom 4 of the device.

Extensions 28 are respectively secured to the stops 26 and are provided with inclined tops 29.

Respectively depending from and secured to the top 1 are a plurality of seats 30, in spaced relation to each other, and which are adapted to seat the pins 7. Each pin 7 is respectively housed and guarded by cages 31, secured on said seats and projecting upwardly and therefrom.

A plurality of replaceers 32 are respectively connected to the ends of each seat in pivotal fashion.

The end of the track 20 is provided with a gate 33 (see Fig. 4) having its ends movable through apertures in said track so that when the ends engage an object the gate is moved upwardly and thereby permits a retarded ball to proceed through said gate.

The top 1 is inclined toward the plunger and has, on each side thereof, inclined alleys 34 that connect an inclined channel 35, and balls not entering aperture 8 pass down the inclined top 45 and alleys.

The channel 35 (Fig. 1) engages a compartment 36 that is adapted to house the balls returning from the top or alleys, and a pivotal gate 37 (Figs. 1 and 3) acts as a stop to said balls in the compartment. A trigger 38 projects from the gate and its end is located beneath a coin slot 39 so that when a coin or the like is dropped through it, said coin will engage the trigger and cause the gate to revolve until its angular side flushes with

the channel floor or bottom and the balls pass over it and into a chute 40. The coin after disengaging the trigger, passes into a receptacle 41, secured to one of the sides 2, and the trigger is caused to return to its normal position due to a spring 42' secured to a seat on said gate and also the top; said spring adapted to rebound when released from a depressed position.

As the ball or balls pass into chute 40 they drop into a container 41 (Fig. 4) disposed between guides 42 that engage slotted members 43 secured to said containers.

The normal position of the container, when not moving, is in an elevated position; due to weights 45 connected to strings 46 that respectively ride pulleys 47; the other ends of said strings respectively connecting with the container.

When the balls are dumped into the container, their weight being greater than that of weights 45, the container is thus caused to descend to the bottom 4; a portion of which is inclined. The base of the container is inclined in similar fashion to the bottom and has an outlet 48 (Fig. 5) over which is a movable door 49 connected in pivotal fashion to the container; said door being provided with a pin 50 that extends through the base so that when it contacts the bottom it will force the door upwardly into open position thereby permitting the balls to pass from the container.

When the balls pass from container 41 it returns to its normal position since the weights cause it to rise until one engages the bottom; whence it comes to rest.

The inclined portion of the bottom 4 leads to an opening 52 in a partition 54 and the balls are adapted to pass down the incline from said container through the opening and into an elevator 40 55; said elevator having connected in pivotal fashion thereto a door 55' registering with said opening when resting on the bottom and permitting the balls to enter from the inclined bottom. A peg 54' is set in partition 54 to prevent movement of said door in one direction thereby preventing balls escaping after entering said elevator. The elevator is provided with an inclined base to permit the balls to emerge from said elevator as hereinafter explained.

50 A shaft 56 formed by said partition and one of said sides, ends and a partition 56' (Fig. 3) is adapted to house the elevator. To the top of said elevator is connected a cable 57 that rides a wheel 58 connected to an axle 59 journaled in bearings 60 on a house 61 having a door 62 therein to permit the escape of balls when the elevator door registers with the door of said house. The other end of said cable engages a handle 63 that rides slides 64 secured to one of said sides.

When the balls pass from the door 62 they enter an inclined track 65 (Fig. 6) in single file, and come to rest near the plunger 10. The ball nearest the plunger enters a stall 66 (Fig. 6) 65 when the plunger is in a "shooting" position, said stall 66 being located adjacent said plunger in a block 67 slidable along a plunger casing 67' and connected by a link 68 that passes through an orifice 69 in said casing 67' of the plunger, 70 and connects to a rod 71, one end of which is provided with a hammer 72 and the other a handle 73.

The plunger's casing is pivoted to the casing 11 by a pin 78 and may be moved about in circumferential fashion and an operative is thus

assisted in aiming the ball to be shot from the plunger.

A spring 79 is disposed between the hammer 72 and end of the plunger casing and when said plunger is withdrawn to shoot a ball; it may be released and the spring will then force the hammer forward causing it to strike a ball and force the latter out of the plunger casing.

When the plunger is pulled outwardly from said casing the block 67 moves in a similar direction until the latter registers with aperture 69, and when it so does, said ball passes through said stall into the plunger casing in front of the hammer and is ready to be expelled therefrom.

The device functions as follows: The pins are 15 resting on seats 30 with their large ends projecting above the top 1, the hammer ejects a ball, and for illustration it hits a pin A. The force of the ball causes the base of the pin to fall from the seat upon its stop 26 (Fig. 7); the 20 ball having returned to compartment 36 by way of alley 34 and channel 35, where it is held against movement in one direction by gate 37.

Another ball is then shot from the plunger, assume, in this fashion it is possible to knock 25 down one or more pins. Let it now be assumed that two pins have been knocked down and a ball is shot that knocks down a pin B; said ball, thereafter, passing through aperture 8.

As the ball passes through aperture 8 it next 30 engages member 12, causing it to tilt (Fig. 2) so that its tongue 14 presses against bar 15 that moves rod 17 thereby bringing the trippers 18 against the seated pins and thus forcing them from their seats 30 thereby causing them to drop 35 on stops 26.

When the pins are on stops 26, the spring 19 forces the rod, trippers and member 12 back to their normal positions. The foregoing action is quickly accomplished since the ball engages member 12 for a short time only, from whence it passes along track 20 causing the latter to move downwardly about axle 22, and as it does the support 23 that is pivotally connected to hanger 24 elevates the base 25 upon which the stops are secured, and the pins being on the stops, rise with the supports and as this takes place the sloped extensions 28 engage the replacers 32 and the latter rides the former and the pins are gradually moved upwardly and inwardly by said replacers and finally are normally positioned upon the seats, and such reseating causes pins to rise above the top.

It is obvious from the foregoing that when a ball is shot from the plunger and enters aperture 8 all the pins are forced from their seats by reason of the hereinbefore mechanical operation; while if a ball merely strikes a pin or pins, knocking them down, and does not enter aperture 8 the pin or pins struck will only be forced from their seat or seats.

The ball, as it proceeds down the track 20, forces the latter downwardly until the former is stopped by gate 33, and when the gate extensions engage a lip 80 (Fig. 2) the gate is forced upwardly and permits the ball to pass.

When the ball passes the gate it falls to the inclined bottom (this is a free ball) where it rolls into the elevator and may be retrieved by 70 raising the elevator.

Of course, all balls that do not go through aperture 8 necessarily pass to compartment 36 and may be played by placing a coin in the slot thus releasing said balls so they may return to 75

track 65 by way of chute 40, container 41 and elevator 55.

The apertures in the top are made larger so that the angular position of the pins may be accommodated.

Having described this invention, what is claimed is:

1. In a bowling alley having an alley board and a plurality of pins extending through enlarged apertures in the alley board, supports beneath the alley board and positioned for supporting the pins in vertical position and projecting above the board, a vertically movable restoring carriage beneath the pin supports, pin rests carried by the carriage and disposed to one side and below the pin supports and onto which the lower ends of the pins are forced upon tilting of the pins by engagement of a ball above the board, the pin rests of the vertically movable carriage forming means whereby the pins resting thereon may be raised to a level

equal to the pin supports and restoring means cooperating with the lower ends of the pins for laterally moving the same onto the pin rests.

2. A device as set forth in claim 1 wherein the restoring means comprises a laterally movable ball actuated frame and arms carried by the frame in the path of the lower ends of the pins.

3. A device as set forth in claim 1 including U-shaped guide members carried by the pin rests and positioned whereby when the lower ends of the pins are forced therein they will move by gravity downwardly and engage the pin supports of the vertically movable carriage.

4. A device as set forth in claim 1 including a reciprocating actuated ball leverage means 15 cooperating with the carriage for raising the same and mechanism controlled by the ball for moving those pins not previously moved by ball engagement whereby they will rest on the supports of the vertically movable carriage. 20

DENNIE ROBERT BAKER.
